UNITED STATES PATENT OFFICE.

FRANK H. HALL, OF BOSTON, MASSACHUSETTS, ASSIGNOR TO WILLIAM FIRTH, OF CHESTNUT HILL, MASSACHUSETTS.

STOP-MOTION.

1,076,980.

Specification of Letters Patent.

Patented Oct. 28, 1913.

Application filed February 1, 1910. Serial No. 541,260.

To all whom it may concern:

Be it known that I, FRANK H. HALL, of Boston, in the county of Suffolk and State of Massachusetts, have invented certain new and useful Improvements in Stop-Motions, of which the following is a specification, reference being had to the accompanying drawings, forming part thereof.

This invention relates to improvements in stop motions for looms, warping machines, and the like, in which the shipper lever is automatically released at the occurrence of a fault in the weaving or because of an abnormal loosening of a thread.

15 As herein illustrated the invention is represented as embodied in a warp stop motion, in which circuit closers are normally sustained by warp threads out of contact with one terminal of an electric circuit, in 20 which circuit is included the magnet of the shipper lever releasing mechanism.

One object of the invention is to so construct a magnetically controlled mechanism, for effecting the release of the shipper handle or lever, that the actuating or knock off member may, under normal conditions, always be in such relation to the armature that said member may be guided to the knock off position, upon movement in the 30 direction to knock off, through the closing of the circuit.

Another object of the invention is to so construct an electrically controlled loom stopping mechanism that the electric circuit is broken through the movement of the mechanism in the loom stopping direction.

Other objects of the invention will appear from the following description.

The invention consists in such peculiar features of construction and combination of parts as shall hereinafter be more fully described and pointed out in the claims.

Figure 1. represents a side elevation, partly in section, of portions of a loom provided with this improved stopping mechanism. Fig. 2. represents a sectional view taken on line 2—2, Fig. 1. Fig. 3. represents an enlarged detail view to show the manner of insulating the terminals of the electric circuit. Fig. 4. represents an enlarged plan view, partly in section, taken on line 2—2, Fig. 1, looking downward, to show the construction of the magnetically controlled knock off or shipper lever release mechanism, the cover being removed, parts

of the bracket being broken away. Fig. 5. represents a sectional view taken on line 5—5, Fig. 4. the cover being in place.

Similar numbers of reference designate corresponding parts throughout.

The improved stop motion is herein shown and described in combination with parts of a loom and as controlled through the medium of an electric circuit having terminals adapted to be connected by circuit closers sustained, under normal conditions, out of contact with one of the circuit terminals by warp threads and adapted upon the breakage of a warp thread or upon the undue loosening thereof to complete the electric circuit whereby the magnet of the stop motion becomes energized. This stop motion may however be utilized to effect the release of the shipper lever or handle of a loom, warping machine or similar mechanism by reason of the closing of an electric circuit through circuit closing devices of any nature at the occurrence of a fault. The particular circuit closing devices herein shown and the terminals with which said closers coöperate do not form part of the present invention and it is not my intention to limit this invention thereby.

As shown in the drawings 5, 6 and 7 represent members of a loom frame, of any ordinary construction, and 8, the end of the breast beam thereof. The shipper lever 9, is mounted in the usual manner and extends through the slot 10 of the bracket 11, mounted on loom member 5, and is engaged with the shoulder 12 of said slot when the loom is in operation. When released from said shoulder 12 shipper lever shifts in the usual manner to stop the loom. Ordinarily the loom frame is of metal and the members 5, 6 and 7 and their connected parts are conductors of electricity and form part of the electric circuit.

Mounted on the loom frame, and preferably in electrical connection therewith is the box or casing 14 which forms the supporting base for the shipper lever knock off mechanism of which the knock off lever 15 is pivotally mounted on the bracket 16, extending from said casing and, at one end, bears against the shipper lever or handle 9, when said lever is in the position shown in Figs. 2 and 4, at which time said lever is held by the shoulder 12 of the bracket 11, said lever 15 having the lip 17 at one end and being

furnished, at the other end, with the electrical contact 18 and the electrical insulation strip 19 which extends laterally beyond the edge of said lever. To the wall of casing 14 is secured the spring 20 which bears against the free end of the knock off lever 15 and acts to press the same outward; said action of spring 20, however, not being sufficient to move said knock off lever against the resistance of the shipper lever 9.

Within the casing 14 is mounted the magnet 21 having pole pieces 22, 22, the ends of the magnet coil being connected with the binding posts 23 and 24, secured in the electric insulation 25, of which post 24 has the spring contact 26 furnished with the end 27 and the bend 28. Slidably mounted in guides formed in the side walls of casing 14 is the armature 29 having the ears 30, 31, located at its respective ends, and in one edge the notch 32, the edges whereof form respectively the shoulder 33 and the cam 34. Engaged with said notch 32 of the armature 29 is the tooth 35 of the slidable member 36 which tooth has the cam edge 37 and the shoulder 38 and is normally held in engagement with notch 32 by the spring 39, secured to said member 36 and to the insulation 25, while provision is made by means 30 of the stud 40 on said member 36 for connecting said member with some moving part of the loom. Casing 14 is also furnished with the cover 41 the edges of which bear against the armature 29 and hold the same 35 in sliding contact with the pole pieces 22, 22, of the magnet 21 while said edges of the cover also limit the sliding movement of the armature by intercepting the ears 30 or 31 thereof. If, now, the member 36 is 40 connected with a moving part of the loom or other machine, to which this knock off mechanism is attached, said member 36 and the armature 29, in engagement therewith will be reciprocated back and forth during 45 the normal operation of the machine. Should, however, the electric circuit be completed through the binding posts 23, 24, and through a source of electrical energy, by any mechanism operated manually or by or 50 through the occurrence of a fault in the operation of the machine, it will be seen that the magnet and its pole pieces 22, 22, will become electrically energized and will attract and hold the armature thereupon, on 55 the outward movement of the member 36, the cam edge 37 will ride over the cam edge 34 of the armature 29 to a position where its end will engage the lip 17 of the lever 15, and thus effect the swinging of said lever, 60 whereby the shipper lever 9 will be moved out of engagement with the shoulder 12 of its retaining device to a point where said shipper lever may move along the slot 15. In such movement the knock off lever 15 65 swings to the position indicated in Fig. 4,

in which the contact 18 is swung away from the spring contact 26 and the end of the insulation 19 bears against said spring contact 26 and the electric circuit is broken.

As herein shown as applied to a loom 70 the stop motion or shipper lever knock off mechanism is actuated by the connecting rod 42 which is connected at one end with one of the usual lay swords 43 and, at the other end, has the slot 44 which is slidably 75 engaged with the stud 40 of the member 34. This slot 44 is of such length, adjustable by the block 45 and the screw 46, as compared with the movement of the lay sword 43 at the point at which the rod 42 80 is secured thereto, that a lost motion of said rod occurs for the greater part of its movement and that the stud 40 is actuated in either direction only as the lay completes its movement in that direction. As the 85 movement of member 36 to actuate lever 15 and knock off the shipper lever 9 does not necessarily exceed one sixth of the movement of the lay and of its sword 43 it is evident, that, during the remaining five 90 sixths of the movement of the lay, the armature 29 is at rest and may be so held by an extremely light electric current supplied to the magnet 21.

The circuit closing mechanism herein 95 shown includes a pair of brackets as 47 which are mounted in the loom and are connected with the arm X of the electric circuit which, as stated above, may be represented by parts of the loom frame. Said brackets as 47 are connected by pairs of terminal guide rods 48, 48 on each pair of which are slidably engaged, drop wires or devices 49, 49 formed of thin sheet metal and having slots 50, 50, engaged with the 100 terminals, and curved at their upper ends so that one or more of said drop devices, normally sustained by warp threads, may upon the failure of the warp threads, move downward and swing toward one of the lease 105 rods 51, 51: these lease rods being mounted in cross arms as 52 which are carried by the plates as 53 sustained by but insulated, electrically, from the brackets as 47 and connected by the arm Y of the electric circuit, 110 through battery 54 or other source of electrical energy with the binding post 23 of the loom stopping mechanism.

When the electric circuit X—Y is closed, by one or more of the drop devices 49, 115 between the guide rod terminals 48 and the lease rod terminals 51 or between any other terminals with which the circuit closers are adapted to coöperate, the magnet 21 of the stop motion is energized and the armature 120 29 is attracted thereby. While the closing of the electric circuit effects, ultimately, the attraction of the armature, by the magnet, without reference to the relative positions of said knock off member 36 and the head 17 125 130

of the lever 15, it is evident that when the armature is attracted by the magnet at or about the limit of movement of the armature 29 and the member 36 in the knocking off direction, toward the left as shown in Fig. 4, the end of the member 36 cannot move away from the armature 29, by reason of the coöperation of the cam edges 34 and 37, as the end of lip 17 prevents such movement 10 of the member 36, and it is necessary to move the armature backward, toward the right as shown in Fig. 4, to a point where the cam 34, while at rest, will act as a guide to direct the cam end 37 of the member 36 outward upon the next knocking off movement of said member 36; this is accomplished by the positive engagement of the shoulder 38 of the member 36 with the similar shoulder 33 of the armature and the positive retraction movement of said knock off member 36.

It is evident that the member 36 may be actuated in its back and forth movement by other means than the rod 42; and it is apparent that the invention is not necessarily limited to the cams 34 and 37 as a means for effecting the movement of the member 36 to a position to engage the lip 17 of the knock off lever 15. Nor is it my intention to limit this invention except as herein claimed.

The elements herein described as the pole pieces 22, 22, may represent any parts of the magnet adapted to be energized by a current of electricity, supplied to the magnet, to attract the armature.

In some cases the lever 15 may be omitted and the member 36 then becomes the knocking off means as, in fact this member always delivers the knock off thrust or blow.

Having thus described my invention I claim as new and desire to secure by Letters Patent—

1. A stop motion comprising an electromagnet, an armature movably mounted and in constant mechanical contact with a pole of said magnet, and knocking off means normally movable in unison with said armature.

2. A stop motion comprising an electromagnet, an armature in slidable contact with a pole of said magnet, and knocking off means normally movable in unison with said armature.

3. A stop motion comprising an electromagnet, an armature movably mounted and in constant mechanical contact with a pole of said magnet, and knocking off means in releasable engagement with said armature.

4. A stop motion comprising an electromagnet, an armature movably mounted and in constant mechanical contact with a pole of said magnet, and knock off means movably mounted with respect to said armature and in engagement therewith.

5. A stop motion comprising an electromagnet, an armature movably mounted and

in constant mechanical contact with a pole of said magnet, and means for effecting the movement of said armature, said means including a knock off device.

6. A stop motion comprising a knock off device movably mounted, and guiding means for said knock off, said guiding means having an armature, and a magnet with a pole of which said armature is in constant contact.

7. A stop motion comprising an electromagnet, an armature movably mounted in contact with a pole of said magnet, said armature having a cam, and a knock off, movable with respect to said armature and adapted to be guided in the knock off direction by said cam.

8. A stop motion comprising a pair of members mounted to move in unison, under normal conditions, and having coöperating means for guiding one of said members with respect to the other when the movement of one of said members is arrested, and electrical controlling means in contact with one of said members, substantially as described.

9. A stop motion comprising an electromagnet, an armature mounted to move in contact with a pole of said magnet, and having a cam, and a knock off member positively engaged with said armature to move the same in one direction and having a cam face adapted to be guided by the armature cam at times.

10. A stop motion comprising an electromagnet, an armature in slidable contact with a pole of said magnet and having a cam and a shoulder, and a knock off member movably mounted and having a tooth engaged between said cam and said shoulder.

11. A stop motion comprising an electromagnet, an armature in slidable contact with a pole of said magnet and having a cam and a shoulder, and a knock off member mounted to slide and swing and having a tooth engaged between the cam and shoulder of the armature, and a spring acting to hold the knock off member in such engagement.

12. A stop motion comprising an electromagnet having pole pieces extending laterally therefrom, an armature slidably mounted and having a face in contact with said pole pieces and having at one edge a cam and a shoulder, a knock off member slidably mounted and having a cam tooth engaged between said cam and shoulder, and a spring, connected with said knock off member and a fixed part of the machine, and acting to hold said cam tooth in engagement with said armature, substantially as described.

13. A stop motion comprising an electromagnet, an armature in slidable contact therewith and having a cam, a knock off member movably mounted and having a cam tooth in engagement with the armature

cam, and a knock off lever, pivotally mounted and having an extension located out of the normal path of said knock off member, with which extension the knock off member is adapted to engage under relative movement of said knock off member and said armature.

14. Stopping or controlling apparatus comprising an armature having a definite path of movement, a knock off member normally operating with said armature, and an electromagnet related to said armature and adapted when energized to arrest said armature at any point in its movement.

15. 15. Stopping or controlling apparatus comprising an armature slidably mounted, a knock off member normally operating with said armature, an electromagnet related to said armature, and means for positively preventing the movement of said armature toward or from said magnet.

16. Stopping apparatus comprising an armature having a linear path of movement, electromagnet means for arresting said armature at any point in its forward movement, and mechanical stopping mechanism having a member controlled as to its operation by said armature.

17. Stopping or controlling mechanism comprising two relatively movable members one of which is an armature and the other an electromagnet, said members being in constant mechanical contact whereby the energizing of said magnet is adapted to arrest said relative movement, and a knock off member releasably engaged with one of said members and adapted to positively operate said member in one direction.

FRANK H. HALL.
